UNITED STATES PATENT OFFICE

JOHN GRANT, OF LOS ANGELES, CALIFORNIA, ASSIGNOR TO BYRON JACKSON CO., OF LOS ANGELES, CALIFORNIA, A CORPORATION OF DELAWARE

WELL ELEVATOR

Original application filed January 11, 1923, Serial No. 611,978. Renewed July 17, 1926. Divided and this application filed October 7, 1930. Serial No. 486,951.

This is a division of my Patent No. 1,781,922, issued November 18, 1930, and relates to well elevators, broadly stated, whether or not said elevator is useful for lifting casing, tubing, or rods. Said invention has for an object the provision of an elevator which ensures that the casing, tubing, or rods, as the case may be, are securely locked within the elevator when the elevator is in operation.

The invention has for a further object the provision of an elevator which will positively indicate if work to be carried by said elevator is not securely held within the elevator.

The invention has for a further object the provision of an elevator which will positively indicate if work to be carried by said elevator is not securely held within the elevator.

The invention has for further objects the provision of a well elevator which is novel in construction, has few working parts, is positive in its operation, and fool-proof as to operation.

With the above and other objects in view, the invention consists in the provision, construction and arrangement of various parts, members and features, all as shown in the drawings, described generally, and finally pointed out in the claims.

In the drawings:

Figure 1 is a fragmentary side elevation of one form of the well elevator;

Figure 2 is a fragmentary top plan view of the well elevator shown in Figure 1, certain parts being in section to show the construction thereof, and with the tubing removed from between the gate and the body of the elevator.

Figure 3 is a fragmentary view, certain parts being in section, of a slightly modified form of well elevator and showing the latch mechanism inoperative.

Figure 4 is a fragmentary view of the well elevator shown in Figure 3, the latch mechanism being shown in part in dotted lines to show the locking of the gate to the body of the elevator.

Figure 5 is a fragmentary edge view of the elevator shown in Figure 4, and taken on the line 5—5 of Figure 4, and looking in the direction of the appended arrows.

Figure 6 is a fragmentary view upon an enlarged scale of the mechanism shown in Figures 3 and 4 for locking the latch mechanism closed.

Figure 7 is a fragmentary top plan view of the means shown in Figure 6; and

Figure 8 is a fragmentary view partly in section of additional means between the body of the well elevator and the gate for swinging the gate from the body if the latch mechanism should fail to function.

Referring with particularity to the drawings and particularly to Figures 1 and 2, inclusive, the well elevator is designated as an entirety by A and as one embodiment thereof, of which a is the body and b the gate. The body, as is customary, is curvedly recessed as

at 1 and the gate is likewise slightly concave as shown at 2, with the gate hingedly connected as at 3 to the body, said gate and body within the curved portion being adapted to confine work such as tubing, casing or rods, as shown at c in Figure 1. The body in the embodiment shown is provided with diametrically opposed spaced arms 4, 5, 6 and 7, and the suspension means or bails d are associated with the arms 4 and 5, as shown at 8 and 9. Ordinarily the well elevator A might be described by saying that the same comprises

two wings or jaws which are adapted to latch around said casing, tubing or rods with the bails fitting over the casing hooks. One feature of the present invention resides in the method by which the bail d is retained upon and held to the body of the well elevator. If

the arms 4 and 5 and 6 and 7 are left spaced apart the suspension means or bail might slip from said arms with disastrous results.

I therefore preferably provide a movably mounted means e which is adapted to close the gap that exists between each pair of spaced arms. The means e is not illustrated and described in detail herein as it is fully described and claimed in the above mentioned copending application.

Means f are provided for releasably holding the body a and gate b in work-embracing relation. The means f is so constructed and operates in such a manner as to "kick" the gate open providing the gate is not securely

latched to the elevator body. It frequently occurs when operating well elevators that the gate is not locked to the body with the result that upon hoisting the gate swings open suddenly dropping the casing or tubing, causing disastrous results either to the operator or to the derrick floor. It has been found expedient to so arrange and relatively associate the moving members which comprise the gate and body, that an improper latching of said members will result in the gate immediately being thrown open so that no mistake as to the latching may be made on the part of the operator.

In the embodiment shown in Figure 2, the means *f* comprises a pivoted latch member 22 which is associated with an enlargement upon the body *a* and within a recess in said enlargement and constitutes an abutment on the body at one side of and adjacent the mouth of the casing receiving recess 1 of the body. The pivot point is shown at 23 and a stop pin at 24 for limiting movement of the latch 22 in one direction. The latch 22 is provided with a curved portion 25, and a spring 26 within the recess of the enlargement is adapted to be received in part within a bore 27 in the latch and held to a wall of the enlargement at its opposite end, said spring acting to move the latch outwardly from said recess.

The gate member *b* carries a nose 28 which is curved corresponding with the curve 25 of the latch 22. When the parts are in the position shown in Figure 2 it will be observed that the curved portions of the nose and of the latch cooperate to effect a locking engagement between the body *a* through the medium of the latch and the gate *b*. To release the latch 22 from the locking engagement with the nose 28 means 29 are provided, said means being joined with the latch 22. An outward pull upon the means 29 will swing the latch inwardly against the spring 26 so that the nose 28 may be released from the latch. The gate *b* may then be swung open by pulling upon a handle 30 associated therewith.

Assume now that it is desired to use the elevator A to carry the casing *c*. The elevator is brought into position so that the casing *c* is received within the body *a* at the part 11 and the gate is swung inwardly to lock the casing or work within the body. The gate, however, unless it is properly latched, will be swung open in the construction shown, for the following reasons: The nose 28 is curved as shown at 31 and this curved portion will engage a marginal portion as 32 of the latch 22. The latch 22 at all times is urged to the limit of its movement by the spring 26, and a swinging of the gate *b* inwardly will cause the curved portion 31 of the nose 28 to slide along the marginal portion 32. If the tip of the nose 28 reaches a point where it would contact with the curved portion 25 of the

latch 22 the latch will immediately be thrown into such a position as to engage the nose and lock the gate to the body. It will be obvious that the latch member will at all times contact with the curved portion 31 of the nose and "kick" or swing the gate about its pivot point 3 to an open position.

The elevator shown in Figures 3 to 8, inclusive, does not differ essentially in principle from the elevator shown in Figures 1 and 2, although certain features are incorporated in a slightly different manner for effecting the locking operation. The elevator shown in Figures 3 to 8, inclusive, is designated as an entirety by B, the body by *h* and the gate by *j* and the latch mechanism as an entirety by *k*. The body, as in the case of the elevator A is recessed as shown at 37 and the gate *j* is slightly recessed in part as shown at 38 to cooperate with the recessed portion 37 so that the gate and the body may confine work when the gate is closed. The gate *j* is pivotally carried upon the body by suitable means such as shown at 39. The usual extension arms are associated with the body *h* and may be of a form such as shown for the elevator A, the bail being omitted for purposes of clearness. The body *h* is recessed as shown by the dotted lines at 40 and the gate member *j* has its normal free end 41 receivable within said recess when the gate is closed. The gate carries part of the latch mechanism; that is to say, the member 42.

Reference to Figure 5 shows that the gate *j* is furcated as shown at 43 with the latch 42 pivotally carried as shown at 44 between said furcations 43. Said latch 42 is curved along its free marginal portion 45 and likewise provided with an arm 46, there being a spring 47 bearing against said arm and having a portion thereof confined within a recess or bore in the gate, as shown at 48. To limit the inward movement or pivotal movement of the latch 42 under pressure exerted by the spring, the gate is provided with a slight extension 49 carrying a pin 50 adapted to contact with the arm 46. The recess 40 within the body *h* has an abutment portion 51 curved to correspond to the curve 45 of the latch so that when the latch swings outwardly and under urgency of the spring, the gate being closed, the curved portion of said latch will slide along the correspondingly curved portion 51 of the body *h*, as illustrated in Figure 4, and effect a locking relation between the gate and the body. Releasing means *m* are provided for disengaging the latch carried by the gate from the body and said releasing means includes a turnable bolt 52 carried between two spaced studs 53 and 54 projecting from the body *h* and said bolt carries a laterally extending member 55 which is received between two furcations 56 and 57 of the body, the said member 55 projecting within the recess 40, as shown in Figures 3 and 4.

The top portion of the member 52 carries an eye 58, there being a sleeve member 59 confined and carried within said eye and a yoke member 60 joined to said sleeve member 59 as by means of a pin 61 joined with the yoke and passed through said sleeve as indicated in Figure 7 in dotted lines. The yoke 60 carries a projecting arm or handle 62. Two positions of the yoke and arm are illustrated in Figures 3, 4 and 6, and it will be observed that the yoke in Figure 6 may be dropped so as to receive within said yoke the projection or stud 54, when the yoke is turned sufficiently so the arm or projecting member 55 will permit the latch 42 to be entirely received within the recess 40. This of course will allow for locking relation between the gate and body, and likewise ensure that the gate will not be freed from the body unless the yoke member is lifted by its handle 62 to such a position that the yoke may be swung to the left which will move the member 55 so that the same may engage a portion of the latch 42 and force it against the spring in order to free the latch from the body,—all as illustrated in Figure 3.

In Figure 4, it will be observed that the recess 40 is likewise provided with a stepped recess 63 which may receive the member 55. The operation of the elevator B is very similar to that of the elevator shown in Figures 1 and 2, in that unless the gate and body are properly latched the tendency will be to swing the gate free from the body, for the latch contacting with the body will tend to swing the gate from the body due to the pressure exerted by the spring 47 against the arm 46 of the latch. Furthermore, the latch has a certain leverage to effect this opening relation, due to the placement of the hinge point of the body and gate.

As an added precaution, it may be desirable, in certain instances, to provide an arrangement substantially as shown in Figure 8, and wherein the gate as in Figures 3 to 7 is received between two furcations 64 and 65 with the hinge connection which constitutes a pin 39 having a surrounding coil spring 66, one end of which is attached to the pin as at 67 and the other end of which is associated as shown at 68 with the gate, the gate to this end being bored slightly larger than the diameter of the pin and the thickness of the spring. The spring is so arranged that the closing of the gate is resisted, the closing tending to tighten the spring, with the consequence that the gate is at all times swung open unless it is properly latched. As before, the gate may be provided with the usual hand grasp 69 for swinging the gate open or shutting the gate.

It is believed that the operation of this device is entirely clear from the description, and that no further details are necessary.

It is obvious that various changes and mod-

ifications and variations may be made in departure from the foregoing description and disclosure, without departing from the true spirit of the invention.

I claim:

1. A device of the character disclosed comprising a body having a casing receiving recess, a gate pivoted to the body, and a latch pivoted in the body adjacent the mouth of the casing receiving recess, a spring for forcing said latch in a direction substantially tangential to the path of the gate and opposite to the direction of closing movement of the gate, and a keeper nose on the gate adapted to be forced outwardly by the latch until it passes the zenith of said latch.

2. A device of the character disclosed comprising a body having a casing receiving recess, a gate pivoted to the body at one side of said recess and a latch receiving chamber formed in the body at the opposite side of said recess, a latch pivoted in said chamber, and a stop for one side of the latch, a spring for pressing said latch toward said stop, a nose on the free end of the gate for engaging with one side of said latch when partially closed and adapted to engage another side of said latch when the gate is fully closed.

3. A device of the character disclosed, comprising connected and relatively movable members adapted to embrace work, and locking means for said members comprising a nose upon one of said members and a movably mounted latch upon the other of said members and adapted to cooperate with said nose to maintain a locked relation between said members; means being provided for disengaging said latch and nose to permit relative movement of said members; said last named means comprising a rotatable member having a part adapted to actuate the latch, and means for releasably locking said rotatable member.

4. A device of the character disclosed, comprising connected and relatively movable members adapted to embrace work, and locking means for said members comprising a nose upon one of said members and a movably mounted latch upon the other of said members and adapted to cooperate with said nose to maintain a locked relation between said members; means being provided for disengaging said latch and nose to permit relative movement of said members; said last named means comprising a rotatable member having a part adapted to actuate the latch, and means for releasably locking said rotatable member.

5. A device of the character disclosed including a body having a casing receiving recess, a gate adapted to be swung across said recess, a gate holding abutment on the body on one side of and adjacent the mouth of said

recess, and means associated with said abutment for releasing the gate.

6. A device of the character disclosed including a body having a casing receiving recess, a gate adapted to be swung across said recess, a gate holding abutment on the body on one side of and adjacent the mouth of said recess, and manually operable means associated with said abutment for releasing the gate.

10. 7. A device of the character disclosed including a body having a casing receiving recess, a gate adapted to be swung across said recess, a movable gate holding abutment on the body at one side of and adjacent the mouth of the casing receiving recess, and means associated with said abutment for releasing the gate.

8. An elevator comprising two members hingedly secured together at one end, said members forming a pipe engaging recess therebetween, a latch pivoted to one of said members at its free end and a stop for one side of the latch, a spring for pressing said latch toward said stop, a nose on the free end of the other member for engaging with one side of said latch and tending to move said latch in a direction resisted by said spring when the latch is in partially closed position, and adapted to engage another side of said latch when the gate is fully closed, said latch being so positioned relative to said nose that pressure exerted on said other side of said latch by said nose tends to move the latch against said stop.

25. 23. Signed at Los Angeles, California, this 1st day of October, 1930.

JOHN GRANT.
